COMBINATION ASH TRAY AND MATCH BOOK HOLDER

Roderick J. MacDonald, Roselle, N. J.

Application August 19, 1950, Serial No. 11,856

Term of patent 14 years

(Cl. D85—2)

To all whom it may concern:

Be it known that I, Roderick J. MacDonald, a citizen of the United States of America, residing in Roselle, in the county of Union and State of New Jersey, have invented a new, original, and ornamental Design for Combination Ash Tray and Match Book Holder, of which the following is a specification, reference being had to the accompanying drawing, forming a part thereof, wherein:

Fig. 1 is a perspective view of a combination ash tray and match book holder, showing my new design;

Fig. 2 is a plan view thereof; and
Fig. 3 is a side view thereof.

I claim:

The ornamental design for a combination ash tray and match book holder, substantially as shown.

RODERICK J. MACDONALD.
